WELDED BOLSTER CENTER BRACE

Charles M. Wright and Louis G. Miller, Bethlehem, Pa., assignors to Bethlehem Steel Company, a corporation of Pennsylvania

Application August 17, 1945, Serial No. 611,044

11 Claims. (Cl. 213—57)

1

Our invention relates broadly to railway car underframes and more particularly to the reinforcement of the central portion of the body bolsters between the center sill members and the manner of assembling the same and more especially to center braces applied to a A.A.R. standard center car sill which comprises a pair of Z-bars disposed with their webs vertically with the top flanges which are longer and thinner than the bottom flanges extending inwardly with their edges welded together thereby forming an inverted U-shaped center sill with outwardly extending bottom flanges.

The cast or welded center braces used for this purpose heretofore have usually been made as a complete separate unit and then riveted to the car sill after the Z-bars were welded together at the junction of the edges of the top flanges.

All of the forces from end buffing and from the vertical load to the truck pass through the rivets attaching the center brace to the center sill. It is, therefore, important that these rivets be well driven and that the center brace fits tight against the center sill.

The railroads specify that these rivets be machine driven by a bull riveter if possible instead of a hand riveter. To do this requires a special movable riveter as the arms of the riveter must operate between the webs of the center sill and between the stiffeners on the center brace.

Considerable trouble has been experienced in getting a tight fit between the center brace and the sills and in getting tight rivets. The inspectors inspect this work very carefully and insist on good workmanship. In order to avoid this difficulty and assure a tight fit and good riveting, we have designed a center brace to meet these conditions. The parts of the new design are made separately in jigs in three pieces, consisting of two side members and one center or locking member.

The side members of the center brace are riveted to the separate Z-bar members of the center sill by stationary bull machines which insures tight fit and tight rivets. After the side members are riveted to the separate Z-bars, the two halves of the center sill are welded together at the junction of their top flanges.

After the edges of the top flanges of the Z-bars forming the center sill are welded together the center locking member of the bolster center brace is inserted and welded to the side members. This locks the two side members together and forms an integral unit.

In our arrangement we have designed a built

2

up bolster center brace of such form as to permit the side members to be secured to the respective halves of the center sill prior to their assembly as a unit and then inserting a separate locking member between the side members to facilitate the welding of the side members together into a single unit, after the two parts of the center sill have been assembled and welded together.

10 Another object of our invention relates to forming and assembling a built up welded center brace, consisting of initially forming two side members and one central or locking member. The side members of the bolster center brace are then riveted by a stationary bull machine to the respective halves of the center sill prior to their assembly as a unit, then welding the edges of the top flanges of the two halves of the center sill together and finally inserting the central locking member of the bolster center brace between the side members and welding it to said side members.

15 A further object of our invention relates to assembling a built up welded bolster center brace, which consists in securing the side members of the bolster center brace to the respective halves of the center sill and then inserting a central locking member between the side members of the bolster center brace and welding it to the said side members.

20 Other objects of our invention will appear hereafter.

Having thus given a general description of the objects of our invention we will now in order to make the same more clear, refer to the annexed two sheets of drawings forming a part of this specification and in which like characters of reference indicate like parts.

25 Figure 1 is a top plan view of a bolster center brace with a portion of the center sill and bolster adjacent thereto indicated in dotted lines, and in which it is shown attached to the center sill by means of rivets.

30 Fig. 2 is a top plan view of one side portion of the bolster center brace shown in Fig. 1 with one half of a portion of the center sill indicated in dotted lines.

35 Fig. 3 is an inner side elevation of one side of the bolster center brace shown attached to one side of the center sill by means of rivets shown in full lines.

40 Fig. 4 is a top plan view of the locking member.

45 Fig. 5 is a vertical longitudinal section taken on the line 5—5 of Fig. 1.

50 Fig. 6 is a bottom plan view of the bolster center

brace shown in Figures 1 to 7, with a portion of the center sill adjacent thereto.

Fig. 7 is a detail vertical section taken on the line 7—7 of Fig. 1.

Referring now to the various characters of reference on the drawings, the numeral 1 indicates the center sill of the car which comprises a pair of Z-bars 2 disposed with their webs 3 vertically and the top flanges 4, which are longer and thinner than the bottom flanges 5, extending inwardly with their end edges welded together as at 6 thereby forming an inverted U-shaped center sill with outwardly extending flanges.

In constructing this bolster center brace it is initially made in three pieces in separate jigs and consists of two side members 7 and 8 and a central locking member 9.

The two side members 7 and 8 are of similar construction but rights and lefts, each having a side wall portion 10 of substantially channel shape with rivet holes 11 for receiving rivets 12 for attaching the side members to the webs 3 of the Z-bars 2 and an inwardly extending top flange 13 of uniform width having rivet holes 14, for receiving rivets 15 for attaching it to the top flanges 4 of the Z-bars 2, and is further provided with an inwardly extending bottom flange 16 of varying width with a greater length in the central portion with an arc shaped recess 17 formed in the edge in line with a portion of the king pin pocket. At an intermediate point the side members 7 and 8 are provided with spaced vertical transversely extending front and back web plates 18 and 19 respectively which have their edges welded to the side wall portions 10 and the top and bottom flanges 13 and 16. A back stop 20 for engaging the rear follower of a draft rigging is welded to each of the forward ends of the side members 7 and 8 and these back stops are further reinforced by means of bracing ribs 21 which connect back stops 20 and the front web plates 18 and are welded thereto and to the side wall portions 10.

As shown more clearly in Figs. 2 and 3 the side members 7 and 8 are first riveted to each half of the center sill then the edges of the top flanges 4 are welded together as at 6, the locking member 9 is then inserted between the side members and the ends welded as at 22 to the inner edges of the front and back web plates 18 and 19.

This locking member 9 is formed of a plate 23 disposed vertically and extending longitudinally between the side members 7 and 8 of the bolster center brace having a vertically extending central semi-cylindrical recess 24. A shorter plate 25 has its ends welded as at 26 to the intermediate portion of the plate 23 and is provided with a central semi-cylindrical recess 27 which is complementary with the recess 24 and adapted to form a king pin pocket 28. The edge of the locking member 9 and the central portions of the bottom flanges 16 are then welded together as at 29 and around the lower end of the king pin pocket as at 30.

As illustrated and described our car bolster center brace is applied to an A. A. R. standard center sill made of a pair of Z-bars, but we do not limit ourselves to this particular type as it could be applied to a center sill formed of a pair of channels or other shaped bars equally as well.

Although we have shown and described our invention in considerable detail, we do not wish it to be limited to the exact construction shown and described, but may use such substitutions, modifications or equivalents thereof, as are em-

braced within the scope of our invention, or as pointed out in the claims.

Having thus described our invention, what we claim as new and desire to secure by Letters Patent is:

1. In a railway car underframe including a center sill formed of a pair of rolled members of Z-section disposed with their webs vertically and the top flanges extending inwardly and their abutting edges welded together to form a center sill of inverted U-section with outwardly extending bottom flanges, a bolster for the car underframe, a bolster center brace between the webs of the Z-section, comprising side members each of substantially channel shape having a side wall and top and bottom flanges, said bottom flange at its central portion having a greater width than the top flange and formed with a recess, a pair of spaced transversely extending web plates welded to each of the channel shaped side members, a locking member comprising a plate structure having its ends welded to the inner edges of the spaced transversely extending web plates and the bottom edges of the locking member to the inner edges of the bottom flanges of the side member, a king pin pocket formed centrally in the locking member registering with the recess formed in the edges of the bottom flanges of the side members, and a welded connection between the edges of the recesses and locking member.

2. A center brace for bolster adapted to be secured between center sill members, comprising a pair of substantially channel shaped side members, each adapted to form a side wall having means for securing them to the center sill members and top and bottom inwardly extending flanges, said bottom flange of each side member having a greater width than the top flange and formed with a central arc shaped recess, spaced front and back transversely extending web plates having a welded connection with each side wall and top and bottom flanges, a back stop welded to the forward end of each of the channel shaped members, bracing ribs connecting the back stop with the front web plate, a locking member provided centrally with a king pin pocket inserted between the side members of the bolster center brace having a welded connection with the inner edges of the web plates and the arc shaped recesses and inner edges of the bottom flanges of the side members.

3. A bolster center brace, comprising a pair of side members each of substantially channel shape having a side wall and top and bottom inwardly extending flanges disposed adjacent to each other in spaced relation, said bottom flanges at the central portion having a greater width than the top flanges, a pair of spaced transversely extending web plates welded to each of the side walls and top and bottom flanges of each of the channel shaped side members with their inner ends in spaced relation to each other, and a locking member comprising a plate structure having its ends mounted between the transversely extending web plates and welded to the inner edges and the bottom edges of the locking member welded to the inner edges of the bottom flanges of the side members.

4. In a railway car underframe including a center sill formed of a pair of rolled Z-sections disposed with their webs vertically and their top flanges extending inwardly and welded together along abutting edges and their bottom flanges extending outwardly to form a center sill of inverted U-section with lateral longitudinal out-

wardly extending flanges, a bolster center brace, comprising a pair of side members adapted to be secured to said rolled Z-sections prior to their union, said side members each of substantially channel shape adapted to form a side wall having means for securing them to the center sill members and having top and bottom inwardly extending flanges disposed adjacent to each other, said bottom flange of each side member having a greater width than the top flanges with their inner edges spaced apart from each other and each formed with a central arc-shaped recess, spaced front and back transversely extending web plates having a welded connection with each of the side walls and the top and bottom flanges with their inner edges spaced apart from each other, and a locking member provided centrally with a king pin pocket inserted between the inner ends of the transversely extending side members of the bolster center brace having a welded connection with the inner edges of the web plates and the arc shaped recesses and the inner edges of the bottom flanges of the side members.

5. A bolster center brace, comprising a pair of side members each of substantially channel shape having a side wall and top and bottom inwardly extending flanges disposed adjacent to each other in spaced relation, said bottom flanges at the central portion having a greater width than the top flanges and each formed with a recess, a pair of spaced transversely extending web plates welded to each of the side walls and top and bottom flanges of each of the channel shaped side members with their inner ends in spaced relation to each other, a locking member comprising a plate structure having its ends mounted between the transversely extending web plates and welded thereto and the bottom edges of the locking member to the inner edges of the bottom flanges of the side members, a king pin pocket formed centrally in the locking member registering with the recesses formed in the edges of the bottom flanges of the side members, and a welded connection between the edges of the recesses and the locking member.

6. A center brace for a bolster adapted to be secured between the center sill members, comprising a pair of substantially channel shaped side members, each adapted to form a side wall having means for securing them to the center sill members and having top and bottom inwardly extending flanges disposed adjacent to each other, said bottom flange of each side member having a greater width than the top flanges with their inner edges spaced apart from each other and each formed with a central arc-shaped recess, spaced front and back transversely extending web plates having a welded connection with each of the side walls and the top and bottom flanges with their inner edges spaced apart from each other, a back stop welded to the forward end of each of the channel shaped members, bracing ribs connecting the back stop with the front web plate, a locking member provided centrally with a king pin pocket inserted between the inner ends of the transversely extending side members of the bolster center brace having a welded connection with the inner edges of web plates and the arc shaped recesses and the inner edges of the bottom flanges of the side members.

7. In a railway car underframe having a pair of rolled members of Z-section disposed with their webs vertically and their top flanges extending inwardly and adapted to be welded along abutting edges to form a center sill of inverted U-shape

section with horizontal flanges at its lower edges, a bolster for the car underframe, a bolster center brace for the bolster between the center sill members, comprising a pair of side members each of substantially channel shape having a side wall secured to the center sill members respectively with top and bottom inwardly extending flanges disposed adjacent to each other in spaced relation, said bottom flanges at the central portion having a greater width than the top flanges and formed with a recess, spaced transversely extending web plates having their edges welded to each of the side walls and flanges of the channel shaped side members, a locking member comprising a vertically disposed plate structure extending longitudinally between the channel shaped side members having its ends and bottom edge welded to the inner edges of the spaced transversely extending web plates and the bottom edges of the locking member to the inner edges of the bottom flanges of the side members, a king pin pocket formed centrally in the locking member registering with the recesses formed in the edges of the bottom flanges of the side members and a welded connection between the edges of the recesses and the locking member.

8. In a railway car underframe having a pair of spaced center sill members each having a vertical web with outwardly extending bottom flanges and inwardly extending top flanges adapted to be welded together at their inner edges to form a center sill, a bolster brace for the bolster between the center sill members, said bolster center brace comprising a pair of side members each of substantially channel shape having a side wall with top and bottom inwardly extending flanges, said bottom flanges having a greater width than the top flanges, spaced transversely extending web plates welded to each of the channel shaped side members, means for securing the channel shaped side members to the webs of the center sill members with the inner ends of the bottom flanges and the inner ends of the transversely extending plates in spaced relation to each other, and a locking member longitudinally disposed between the channel shaped side member comprising a plate structure having its ends welded to the inner edges of the spaced transversely extending web plates and the bottom edges of the locking member welded to the inner edges of the bottom flanges of the side members.

9. In a railway car underframe having a pair of spaced center sill members each having a vertical web with outwardly extending bottom flanges and inwardly extending top flanges adapted to be secured together along their abutting edges to form a car sill, a bolster for the car underframe, a center brace for the bolster between the center sill members, comprising side members each of substantially channel shape having a side wall with top and bottom inwardly extending flanges, said bottom flanges at the central portion having a greater width than the top flanges and each formed with a recess, a pair of spaced transversely extending web plates welded to each of the channel shaped side members and extending inwardly the width of the bottom flange, means for securing the channel shaped side members to the webs of the center sill members with their inner edges in spaced relation to each other, a locking member comprising a plate structure disposed longitudinally between the channel shaped side members having its ends welded to the inner edges of the spaced transversely extending web plates and the bottom edges of the locking mem-

ber welded to the inner edges of the bottom flanges of the side members, a king pin pocket formed centrally in the locking member registering with the recesses formed in the edges of the bottom flanges of the side members, and a welded connection between the edges of the recesses and the locking member.

10. In a railway car underframe including a pair of rolled members of Z-section disposed with their webs vertically and their top flanges extending inwardly and their abutting edges welded together to form a center sill of inverted U-section with outwardly extending bottom flanges, a bolster for the car underframe, a bolster center brace between the webs of the Z-sections, comprising a pair of side members each of substantially channel shape having a side wall and top and bottom inwardly extending flanges disposed adjacent to each other in spaced relation, said bottom flanges at the central portion having a greater width than the top flanges, a pair of spaced transversely extending web plates welded to each of the side walls and top and bottom flanges and extending inwardly the width of the bottom flanges and a locking member provided centrally with a king pin pocket disposed longitudinally between the channel shaped side members of the bolster center brace having its ends welded to the inner edges of the transversely extending web plates and the inner edges of the bottom flanges of the channel shaped side members.

11. In a railway car underframe having a pair of rolled members of Z-section disposed with their webs vertically and their top flanges extending inwardly and adapted to be welded along abutting edges to form a center sill of inverted U-shape section with horizontal flanges at its lower edges, a bolster for the car underframe, a bolster center brace for the bolster between the center sill members, comprising a pair of side members each of substantially channel shape having a side wall secured to the center sill members respectively with top and bottom inwardly extending flanges

5 disposed adjacent to each other in spaced relation, said bottom flanges at the central portions having a greater width than the top flanges and each formed with a recess, a pair of spaced transversely extending web plates having their edges welded to each of the side walls and flanges of the channel shaped side members, a locking member comprising a vertically disposed plate structure extending longitudinally between the channel shaped side members having its ends welded to the inner edges of the spaced transversely extending web plates and the bottom edges of the locking member welded to the inner edges of the bottom flanges of the side members, a vertically 10 extending semi-cylindrical recess formed in the central portion of the locking member, a shorter plate than the locking member welded to the central portion of the locking member having a vertically extending semi-cylindrical recess formed 15 therein complementary with the recess in the locking member to form a king pin pocket registering with the recesses formed in the edges of the bottom flanges of the side members, and a welded connection between the edges of the recesses and the locking member.
